UNITED STATES PATENT OFFICE.

GEORGE CLINTON CARR, OF NELSON, KENTUCKY.

IRONING-BOARD.

1,082,403.

Specification of Letters Patent. Patented Dec. 23, 1913.

Application filed August 20, 1912. Serial No. 716,066.

To all whom it may concern:

Be it known that I, GEORGE C. CARR, a citizen of the United States, residing at Nelson, in the county of Muhlenberg and State 5 of Kentucky, have invented new and useful Improvements in Ironing-Boards, of which the following is a specification.

The present invention relates to improvements in ironing boards.

10 In carrying out my invention it is my purpose to construct an ironing board provided with a collapsible support which may be readily set up to support the board, and which may be easily and quickly folded 15 against the board to occupy a comparatively small space when the board is not in use.

A still further object of the invention is the provision with an ironing board, of a support which may be readily adjusted so 20 as to sustain the board at various heights to accommodate various operators.

With the above recited objects in view and others which will appear as the nature of the invention is more fully disclosed the 25 improvement resides in the construction, combination and arrangement of parts set forth in the following description and falling within the scope of the appended claim.

In the drawing, Figure 1 is a perspective 30 view of an ironing board constructed in accordance with the present invention, and showing the same in its set up position. Fig. 2 is a detail transverse sectional view taken approximately upon the line 2—2 of 35 Fig. 1. Fig. 3 is a view of the board with the support folded thereon.

Referring now to the drawing in detail, the numeral 1 designates an ordinary ironing board, the same being provided adjacent its rear or larger end, and upon its under face with a transversely arranged ledge 2 which terminates a slight distance away from the longitudinal edges of the said board. The ledge 2 is formed adjacent its 45 lower face, and upon its opposite ends with rounded extensions 3, the same forming trunnions for a pair of forwardly extending legs 4. Centrally connected with the leg members 4, and through the medium of a 50 transversely extending rung 5, is a second pair of leg members 6. The pairs of leg members 4 and 6 respectively, are approximately in the form of an X in side elevation, when the support is in a set up position. The upper extremity of the leg members 6, or the ends thereof lying directly be-

neath the board 1, when the support is set up, are connected through the medium of a transversely arranged member 7, the said member being centrally provided with a depression 8 which is adapted to receive a longitudinally extending strip 9 attached to the under face of the board 1, and forming a bearing strip for the board. The opposite ends of each of the pairs of leg members 4 and 6 are connected through the medium of suitable rungs 10 and 11, respectively, and pivotally connected with the rung 11 is a pair of spaced leg sustaining members 12 and 13, respectively. Each of 70 these members comprises an elongated substantially rectangular element, and each of the said elements is formed adjacent its free end with a plurality of spaced depressions or notches 14, which extend inwardly from 75 the under edges of the said members, and which are also adapted to co-operate with the rung 10 to sustain the legs in proper spaced position, and the board 1 at a proper height with relation to the floor upon which 80 the legs are arranged. The opposite edges of the members 12 and 13 are provided with depressions 15, and these depressions are adapted to engage with the rung 5 when the legs and sustaining members are in a folded 85 position, as illustrated in Fig. 3 of the drawing.

From the above description, it will be noted that the parts have been generally described as when the device is in its set up 90 position, and from the said description taken in connection with the accompanying drawing, the simplicity, durability and cheapness of the structure, as well as the method of setting up the board support, or 95 collapsing the same, will, it is thought, be perfectly apparent without further detailed description.

Having thus described the invention, what I claim is:—

An ironing board having a centrally arranged longitudinally extending bearing strip upon its under face and being provided with a transversely arranged ledge, the ends of which being formed with trunnions, forwardly extending leg members pivotally connected with the trunnions and having their free extremities connected by a rod, rearwardly extending leg members having their upper ends connected by a 110 transversely arranged member which is centrally provided with a slot that is adapted

to receive the strip of the board when said board is in active use, a rung member centrally connecting the leg members, a rung connecting the lower extremities of the rear-
wardly extending leg members, a pair of leg-
sustaining members pivotally connected with
the last named rung and extending longitudi-
nally of and in parallel relation with the
board, each of said members having their
bottom longitudinal edges adjacent the for-
ward ends thereof provided with a plurality
of registering notches which are adapted to
engage with the rung connecting the for-

wardly extending leg members, and the said
sustaining members having their upper lon-
gitudinal edges at a point rearwardly of
said notches formed with depressions adapt-
ed to receive the connecting rung of the leg
members when the legs are folded against
the board. 15

20 In testimony whereof I affix my signature
in presence of two witnesses.

GEORGE CLINTON CARR.
